ELECTRIC SIGNAL SYSTEM

Filed Sept. 22, 1927

UNITED STATES PATENT OFFICE

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTRIC SIGNAL SYSTEM

Application filed September 22, 1927. Serial No. 221,152.

This invention relates to signal systems, and more particularly to an electric signal system adapted for use on railway trains.

An object of my invention is to provide a train signal system by the use of which a trainman may signal the engineman from any car of a train and by which the engineman may cause his reply signal to be transmitted to the car station from which the trainman's signal originated, and, further, by which the engineman may signal any number of car stations which have been previously rendered operative by the trainman.

Another object of the invention is to provide a train signal system in which the signal device for the trainman is sounded by means of fluid under pressure, the flow of which is electrically controlled by an electric circuit operated by the engineman.

These and other objects will appear in the following more detailed description of the invention.

In the accompanying drawing, the single figure is a diagrammatic view of a train signal system embodying my invention.

According to my invention, the locomotive or controller car of a railway train is provided with an engineman's switch having a movable contact arm 2 which is normally held in contact with a contact point 3 by a spring 4 or any other desired means. The locomotive is further provided with a signal indicating device such as an alternating current buzzer 5. The contact point 3 of the switch is connected to ground at 6 and the switch arm is connected with one terminal of the buzzer 5, while the other terminal is connected with a train wire 7.

Each car of the train may be provided with a trainman's switch device 8, an induction coil 9, a signal indicating device 10, a rectifier 11, and a source of electric current, such as a battery 12.

The switch device 8 comprises a casing 13 which contains a sliding contact member 14 having an operating stem 15 adapted to be operated by a lever 16 having operating arms 17 and 18, each having an operating cord 19 connected therewith. Mounted on the casing 13 there are fulcrum pins 20 and 21 which are

so disposed that when the arm 17 is operated the lever 16 turns about the fulcrum pin 20 to operate the stem 15, and when the arm 18 is operated the lever turns about the fulcrum pin 21 to operate said stem.

The contact member 14 is provided with contacts 22 and 23 and is normally maintained in the position shown in the drawing by the action of a spring 24 mounted in the casing. This member 14, when moved a predetermined distance from its normal position, engages a stop 25 formed on a plug having screw-threaded connection with the casing. In order to prevent rotative movement of the contact member 14, a guide bushing 26, having screw-threaded engagement with the casing 13, is provided with a pin 27 which engages in a groove formed in the contact member. Arranged within the casing 13 are contact terminals 28, 29, 30, and 31. The contact terminal 28 is connected with one end of a coil 32 of the induction coil 9, the opposite end of such coil 32 being connected with a contact 33 with which an interrupter 34 is adapted to contact. The proper contact between one end of the interrupter 34 and the contact 33 is insured by the action of a spring 35. The opposite end of this interrupter 34 is connected to ground at 36 and is also connected to one end of a coil 37 of the induction coil 9, the other end of which coil 37 is connected with the contact terminal 31. The induction coil is also provided with the usual armature or core 38 with which the interrupter 34 is adapted to contact. The contact terminal 29 is connected with the positive terminal of the battery 12, the negative terminal of such battery being connected to ground at 39. The contact terminal 29 and the positive terminal of the battery 12 are also connected to a tine 40 of a jack, which jack has a tine 41 connected with a magnet portion of the signal indicating device 10, the rectifier 11 being interposed between the magnet and the tine 41 to permit current to flow in the direction as indicated by the arrow in the drawing. The magnet portion of the signal indicating device 10 is also connected, by a wire 42, to the train wire 7. The contact terminal 30 is

connected, by a connection 43, with the train wire 7, there being a condenser 44 interposed in this connection for preventing the flow of direct current through this connection to the induction coil 9 when the contact 23 is in contact with the contact terminals 30 and 31.

The signal indicating device 10 may comprise a casing containing the hereinbefore mentioned magnet portion and also containing a valve 45 for controlling the flow of fluid under pressure from a passage 46 to a passage 47 leading to a sounding device such as a whistle 48. The passage 46 is connected with a reservoir 49, by a pipe 50. The casing 10 also contains a valve 51 for controlling the flow of fluid under pressure from the brake pipe (not shown) or any other suitable source of fluid pressure to the passage 46, pipe 50 and reservoir 49. The valves 45 and 51 have 15 fluted stems which are adapted to engage each other, so that the operation of one valve will ensure the proper operation of the other. Normally the valve 45 is in its open position and the valve 51 is in its closed position as 20 shown in the drawing and both valves are maintained in such positions by a spring 52 mounted in the casing and acting upon the valve 51.

Interposed in the pipe, through which fluid under pressure is supplied to the passage 46 and reservoir 49, there is a check valve device 53 which, when an emergency application of the brake is made, prevents the fluid under pressure in the reservoir from flowing 30 back to the brake pipe or other source of supply, thus maintaining sufficient pressure in the reservoir to operate the whistle 48.

Assuming the several parts of my invention to be in their normal positions, as shown 40 in the drawing, and the trainman desires to signal the engineman, the trainman pulls the cord 19 until the contact member 14 comes to rest against the stop 25, at which time the contact 22 will connect the contact terminals 28 and 29, and the contact 23 will connect the contact terminals 30 and 31, which permits current to flow from the positive terminal of the battery 12 to the coil 32 and therethrough to the contact 33 and, as the interrupter 34 is 50 normally held in contact with the contact 33, by the spring 35, the current will flow therethrough to ground 36. The current thus flowing through the coil 32, magnetizes the armature or core 38 of the induction coil 9, so that the interrupter 34 is drawn out of contact with the contact 33, thus opening the circuit from the battery 12 and interrupting the flow of current through the coil 32. When the flow of current is thus interrupted, the 55 armature becomes demagnetized and the spring 35 causes the interrupter 34 to be again moved into contact with the contact 33 which again closes the circuit, and these operations continue so long as the trainman 60 maintains the contact member in its depressed

position. The making and breaking of the circuit through the coil 32 causes an alternating current to be induced in the coil 37 which flows through the contact terminal 31, contact 23, contact terminal 30, wire 43 and 70 through the condenser 44 to the train wire 7, then through the buzzer 5, switch arm 2 and contact 3 to ground 6, thus causing the buzzer 5 at the engineman's station to operate. By operating the contact member up and down, 75 the trainman may cause any predetermined signal to be sounded at the engineman's station.

For the trainman to receive a signal initiated by the engineman or in reply to his 80 signal to the engineman, he must insert a plug 54 between the tines 40 and 41 of the jack at each of the car stations where he desires the engineman's signal to sound. When the plug 54 is inserted between the tines 40 and 41 of 85 the jack, current is permitted to flow from the positive terminal of the battery through the jack, rectifier 11, magnet portion of the signal device 10, train wire 7, buzzer 5, arm 2 and contact 3 of the engineman's switch to 90 ground 6, thus energizing the magnet portion of the signal device, which causes the valve 45 to seat and the valve 51 to unseat. When the valve 51 is thus unseated, fluid 95 under pressure flows past the check valve 53 and valve 51, through passage 46 and pipe 50 and charges the reservoir 49. If the engineman desires to signal the trainman, he moves the switch arm 2 out of contact with the contact 3 and breaks the circuit just described, causing the magnet portion of the signal device 10 to become deenergized, which permits the spring 52 to seat the valve 51 and unseat the valve 45. When the valve 45 is thus unseated, fluid under pressure from the 100 reservoir 49 is permitted to flow through pipe 50 and passage 46 past the valve 45 and through passage 47 to the whistle 48, causing the whistle to sound. By making and breaking the circuit by operating the switch 110 arm 2, the engineman may cause the whistle 48 to sound any predetermined signal to the trainman.

Should the trainman cause the contact member 14 to be depressed to signal the engineman, when the plug 54 is in its proper 115 position between the tines 40 and 41 of the jack, direct current will flow through the jack, rectifier 11, magnet portion of the signal device 10, train wire 7, buzzer 5 and engineman's switch, to ground 6, thus energizing said magnet portion, which causes the valve 45 to seat and the valve 51 to unseat, so that the reservoir 49 will be charged and the whistle 48 will not be supplied with fluid 120 under pressure and will remain silent. It will here be noted that the condenser 44 will prevent the flow of direct current through the coil 37 of the induction coil 9 to ground 36, which current, if the condenser were omitted, 125 130

flowing through the coil 37, would magnetize the armature or core 38, which would cause the interrupter 34 to be moved and held out of engagement with the contact 33 and would thus render the induction coil 9 inoperative, so that it would be impossible for the trainman to signal the engineman when the plug 54 is inserted in the jack.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. In a train signal system, the combination with a single train wire, of an electric signal indicating device on the head vehicle of a train interposed in said train wire and operative by alternating current, a switch device on said vehicle normally connecting said train wire to ground, a source of direct current on each of the other vehicles of the train permanently connected to ground, means on each of said other vehicles adapted to transform direct current into alternating current, a switch device on each of said other vehicles of the train operative to cut the local source of current in circuit with the local means and to cut said local means in circuit with said train wire to supply alternating current to said electric signal device, a fluid pressure operated signal device on each of said other vehicles, an electro-magnet on each of said other vehicles operative upon energization to prevent fluid under pressure from flowing to the local fluid pressure operated signal device and operative upon deenergization to supply fluid under pressure to the local fluid pressure operated signal device, and means on each of said other vehicles for cutting said source of current in circuit with said electro magnet to energize it, the switch on the head vehicle being operative to a position to open and close the circuit through the electro-magnet cut-in circuit on any of said other vehicles.

2. In a train signal system, the combination with a single train wire, normally connected to ground, of an electrically controlled signal device on the head vehicle of a train interposed in said train wire and operative by alternating current, a fluid pressure operated signal device on each of the other vehicles of the train, electro-magnetic means on each of said other vehicles for controlling the operation of a local fluid pressure operated signal device and connected with said train wire, a source of direct current on each of said other vehicles having one terminal connected to ground and adapted to supply current to the signal device on the head vehicle and to the local electro-magnetic means, means on each of said other vehicles for forming the direct current from the local

source to alternating current to operate the signal device on the head vehicle, means on each of said other vehicles for controlling the operation of the electrically operated signal device, and switch means on the head vehicle operative to connect and disconnect said train wire to and from ground for opening and closing the circuit through the local source of current and local electro-magnetic means to control the operation of said local fluid pressure operated signal device.

3. In a train signal system, the combination with a train wire normally connected to ground, of an electrically controlled signal device on the head vehicle of a train interposed in said train wire and operative by alternating current, a fluid pressure operated signal device on each of the other vehicles of the train, electro-magnetic means on each of said other vehicles for controlling the operation of the local fluid pressure operated signal device and connected to said train wire, induction means on each of said other vehicles connected to said train wire adapted to transform direct current to alternating current, a source of current on each of said other vehicles for supplying direct current to the local induction means and to the local electro-magnetic means, means on each of said other vehicles operative to connect and disconnect the local source of current into and out of circuit with the local induction means to operate said electrically controlled signal device, a switch device on each of said other vehicles operative to cut the local source of current in circuit with the local electro-magnetic means, and means on the head vehicle operative to connect and disconnect the train wire to and from ground to control the flow of current through the local electro-magnetic means for controlling the operation of the local fluid pressure operated signal device.

4. In a train signal system, the combination with a single train wire, of an electric signal device interposed in said train wire on the head vehicle of the train and operative by alternating current, a switch device on said vehicle normally connecting said train wire to ground, a source of direct electric current on each of the other vehicles of the train, a fluid pressure operated signal device on each of said other vehicles, a direct current electro-magnetic means on each of said other vehicles permanently connected to said train wire, said electro-magnetic means being operative upon energization to close off the supply of fluid under pressure to the local fluid pressure operated signal device and operative upon deenergization to supply fluid under pressure to the local signal device to sound a signal, a switch device on each of said other vehicles operative to a position to connect the local source of current in circuit with the local electro-magnetic

means for energizing it, the switch device on the head vehicle being operative to a position to disconnect the train wire from ground for deenergizing said local electro-magnetic means, means on each of said other vehicles for transforming direct current from the local source of current into alternating current, a second switch device on each of said other vehicles operative to a position to connect the local source of current in circuit with the local electro-magnetic means and to establish a connection over which alternating current from said local electro-magnetic means is supplied to said train wire to operate the signal device on the head vehicle, and means for preventing the flow of direct current from said train wire to said electro-magnetic means when both of the local switch devices are in their circuit closing positions.

5. In a train signal system, the combination with a single train wire, normally connected to ground, of an electrically controlled signal device on the head vehicle of a train interposed in said train wire and operative by alternating current, a fluid pressure operated signal device on each of the other vehicles of the train, electro-magnetic means on each of said other vehicles for controlling the operation of a local fluid pressure operated signal device and connected with said train wire, a source of direct current on each of said other vehicles having one terminal connected to ground and adapted to supply current to the signal device on the head vehicle and to the local electro-magnetic means, means on each of said other vehicles for transforming the direct current from the local source to alternating current to operate the signal device on the head vehicle, means on each of said other vehicles for controlling the operation of the electrically operated signal device, switch means on the head vehicle operative to connect and disconnect said train wire to and from ground for opening and closing the circuit through the local source of current and local electro-magnetic means to control the operation of said local fluid pressure operated signal device, and means for preventing the flow of direct current from said train wire to the current transforming means when said current transforming means is cut in circuit with the train wire and when said source of current is cut in circuit with said electro-magnetic means and train wire.

In testimony whereof I have hereunto set my hand.

THOMAS H. THOMAS.
